UNITED STATES PATENT OFFICE.

WILLIAM DICHMANN, OF OSHKOSH, WISCONSIN, ASSIGNOR OF ONE-HALF TO CHARLES A. WAKEMAN, OF OSHKOSH, WISCONSIN.

APPARATUS AND METHOD FOR MAKING TUBULAR PACKING-PADS.

1,097,792.

Specification of Letters Patent.

Patented May 26, 1914.

Application filed November 1, 1912. Serial No. 729,038.

To all whom it may concern:

Be it known that I, WILLIAM DICHMANN, a citizen of the United States, and resident of Oshkosh, in the county of Winnebago 5 and State of Wisconsin, have invented certain new and useful Improvements in Apparatus and Methods for Making Tubular Packing-Pads; and I do hereby declare that the following is a full, clear, and exact description thereof.

My invention refers to tubular packing pads, its object being to provide a simple, effective and rapid apparatus and method for forming such pads from continuous 15 strips of fibrous material, preferably paper.

The invention contemplates an apparatus and method whereby an enveloping strip is passed through a standard type of tubular forming sleeve, first receiving parallel lines 20 of glue at a predetermined distance from its edges and is then centrally coated with paraffin between the glue lines, the paraffin extending approximately the width of the completed tube. A second or protecting strip 25 is then fed from a roll upon the upper face of the enveloping strip and a third strip, after being corrugated and coated with adhesive material upon its under side, is piled upon the protecting strip to which it is 30 caused to adhere. The corrugated or embossed cushion strip, incidental to the enveloping strip being folded and lap-seamed, is also caused to adhere to the seam side of said enveloping strip, the lap-seam being supplied with adhesive material through the 35 medium of a glue-roller which is disposed at the discharge mouth of the tubular sleeve. The next step in the operation is to admit the tube between scoring draw-rolls whereby 40 the transverse corrugations of the cushion strip are broken down in parallel lines, the completed tube being then severed in desired lengths by cutting means. It is also within the scope of my invention in some 45 instances to dispense with paraffining one face of the finished tubes.

With the above objects in view the invention consists in what is herein shown and described with reference to the accompanying 50 drawings and subsequently claimed.

In the drawings Figure 1 represents a longitudinal sectional view of an apparatus in the form of a machine embodying the mechanical elements employed in the method

of forming packing pads in accordance with 55 my invention; Fig. 2, a side elevation looking toward the gear side of the machine; Figs. 3, 4 and 5, detailed cross-sections, the sections being indicated by lines 3-3, 4-4 and 5-5 respectively, of Fig. 1; Fig. 6, a 60 detailed cross-section of the discharge end of the tube-forming sleeve, the section being indicated by line 6-6 of Fig. 1; Figs. 7 and 8, cross-sections of the machine as indicated by lines 7-7 and 8-8 respectively of Fig. 1; 65 Fig. 9, a plan view of portions of the several strips which are combined to form the finished product; Fig. 10, a longitudinal sectional view of a portion of the finished pad, and Fig. 11, a cross-section of the same. 70

Referring by characters to the drawings, 1 represents longitudinal struts of a frame and mounted upon the struts at the feed end of said frame is a pair of side-plates 2 provided with bearings for trunnions of a hollow corrugating or embossing roll 3, the corrugations of which roll as shown are longitudinally disposed and adapted to mesh with corresponding corrugations of a similar hollow roll 3', the trunnioned ends of the same 80 being journaled in spring-pressed boxes that are slidably mounted in suitable apertures with which the side plates 2 are provided. Motion is imparted to the upper roll 3 through an endless belt 4 that connects a 85 pulley that is affixed upon one of the trunnions of said upper roll and a similar pulley carried by a counter-shaft 5, the lower roll 3' either being driven from the upper roll by spur-gears or through their intermeshed cor- 90 rugations. Journaled in the side frame forwardly of the corrugated set of rolls is a feed-roll 6 that is preferably covered with a friction band, the same being positively driven by a chain-belt 7 that connects a 95 sprocket-wheel carried by the lower roll 3' and a similar sprocket-wheel that is mounted upon the shaft 7' of the roll, the said sprocket being indicated by dotted lines in Fig. 1.

A glue-distributing roller 8 is also mounted in suitable journals with which said side-plates are provided, the same being revoluble in a glue-pot 3' and is interposed between the paper feed-roll and set of corrugated 100 rolls as shown. This glue distributing roll 8 is positively driven by engagement of a sprocket-wheel carried upon its shaft with

one stretch of the chain belt 7. Located between the glue-roller 8 and feed roller 6 is an idle guide spool 9 that serves as a guide for a protecting strip of paper B, which strip of paper is wound upon a reel 10 that is mounted in suitable bearings formed in the side plates above the corrugating rolls. A second reel 10' similarly mounted upon the frame is provided for the reception of an enveloping paper strip A, which strip, as shown, passes from said reel, over an idle spool 11 and about the feed roll 6 and from thence said strip passes through a tube-forming sleeve 12 that is supported from the frame struts. The stretch of the enveloping strip A, between the spool 11 and feed roller 6, in its travel first passes over a pair of spaced glue-distributing disks 13 and thereafter over the face of a paraffining roller 14, whereby said strip receives parallel lines of glue at predetermined points from its edges, the strip being also paraffined intermediate of said glue lines for a width approximately equaling the width of the completed pad. The gluing disks 13 are arranged to revolve in a suitable glue-pot 13' while the paraffin roller 14 is supplied from a well 14', which well is provided with a double wall whereby steam may be admitted for the purpose of maintaining its contents at the desired consistency. The gluing disks 13 and paraffin roller 14 are driven in the same direction and speed as that traveled by the enveloping strip A, the drive being effected through suitable sprocket-wheels with which said disk and roller are provided, the said sprocket-wheels being engaged by a chain-belt 15 that is also mounted upon a sprocket-wheel carried by the counter-shaft 40 5 as indicated in Fig. 1 of the drawings.

From the foregoing description it will be seen that the enveloping strip A constitutes the base member of the pad, upon which is first laid the reinforcing or protecting strip B. A third paper strip constituting a filler or cushion C is mounted upon an overhead reel 16, from which reel it is fed between the set of corrugating rolls 3 and 3', being thus transversely fluted or corrugated and from thence it travels toward the mouth of the tubular forming sleeve 12, receiving glue upon the high bottom faces of its corrugation, in its travel, by engagement with the face of the glue-roller 8. Prior to entering the mouth of the forming sleeve said corrugated strip is laid upon the upper face of the reinforcing or protecting strip B and traveling at the same rate of speed as the latter, and together with the enveloping strip, the entire series engage each other and enter said sleeve. The pad is folded in tube form prior to its discharge from the sleeve, being thereafter sealed longitudinally and delivered to cutting mechanism, to be hereinafter described, by passing between upper

and lower scoring draw rolls 17, 17' respectively, which draw rolls in conjunction with the several driven rolls at the feed end of the apparatus serve to impart a positive feed to the three strips without appreciable tension thereon, it being borne in mind that all of said strips are arranged to travel at the same rate of speed and that the enveloping strip in its folded form constitutes the active member of the series due to its engagement between the draw rolls. The reinforcing strip B and the transversely corrugated cushion strip C are of a uniform width and approximately equal the width of a completed pad and hence when the draw rollers grip the upper and lower faces of the folded enveloping strip of the completed pad it is evident that there is no independent draw upon the reinforcing and cushion strips that would tend to distend or flatten the corrugations in the latter. It is further apparent that the corrugated cushion strip, in its travel through the forming sleeve 12 at the discharge end of the apparatus, will be caused to adhere to the upper face of the reinforcing strip and to the under surface of the enveloping strip upon its seamed side, this adhesion being effected through the glue lines that are placed on said enveloping strip by means of the disks 13. As the folded enveloping strip A passes beyond the discharge mouth of the tubular forming sleeve 12 the lapped edges thereof are arranged to receive a coating of adhesive material from an obliquely disposed disk 18, the periphery of which disk in turn is supplied with glue through a vertically disposed revoluble disk 18' that is partly submerged in a glue-containing reservoir 19.

The above described glue mechanism together with the forming sleeve forms no part of my invention, the same being clearly shown in a patent issued to me March 21, 1911, for improvements in pad-making machines, No. 987440.

After the lapped edges of the pad have received a coating of glue the completed pad passes between the draw rollers 17, 17', the upper one of which set is provided with a series of spaced annular flanges 17'', which flanges constitute scoring members, whereby as the pad travels between the rolls it is sealed and scored longitudinally at predetermined distances, to thus break down the transverse corrugations of the cushion strip upon the seam side of the pad in order to render the same pliable longitudinally so that it can be folded about any article for packing the same for shipment for protecting its finish. As shown the score-roller 17' is journaled in boxes which are under spring control whereby the said roller is rendered yieldable to compensate for variations in the thickness of the pad.

For cutting the pads into predetermined lengths I provide an adjustable cutting mechanism which mechanism comprises a shear roller 20 having a shaft 21 that is journaled in side-plates 2' with which the frame struts are provided at the discharge end of the machine, it being understood that said side-plates also form supports for the scoring draw rolls. Suitably journaled 5 within the side plates 2' and above the shear-roller 20 is a cutting roller 22, which roller carries a blade 22' that is adapted to sever a pad with each revolution of the said roller, these rollers being in spur-gear 10 connection. The shaft 21 of the shear-roller has loosely mounted thereon a spur-gear wheel 23, which gear-wheel carries a pin 23' that with each revolution of the same is adapted to engage a weighted arm 24, the 15 same being fast upon the shear roller shaft 21. This spur-gear wheel receives its motion from a pinion 25 that is carried upon the shaft of the lower draw roller 17', the said pinion being in meshed engagement 20 with an idle gear-wheel 25', which in turn meshes with the gear-wheel 23. To vary the length of cut of a pad the gear-wheel 25' is detachably supported at the end of a slotted arm 26, the opposite end of which is mounted 25 about the shear-roller shaft 21 and held in its adjusted position by means of a locking nut and its bolt 27, which bolt passes through the slot in said arm 26, and also a slot that is disposed at a right angle thereto, 30 the same being formed in the adjacent side-plate 2'. Hence when it is desired to vary the length of cut of the pad the gear-wheel 25' may be replaced by a larger or smaller idle gear-wheel, whereby motion is transmitted from the lower draw roll 17' to the gear-wheel 23 at a higher or lower speed. Hence it will be observed that with each rotation of the gear-wheel 23, in the direction indicated by the arrow, the pin 23' thereof 35 will pick up the weighted arm 24 and rotate the same through approximately a half revolution from the position it assumes in Fig. 1 of the drawings and as said weighted arm passes through its center of gravity, 40 by positive lift imparted thereto through the pin 23', it is apparent that said arm will drop forward and describe a half revolution through its weight control and thus impart a corresponding half revolution to the cutting roller 22 and its blade 22', whereby 45 the same will sever a pad and assume the position shown in Fig. 1 of the drawings, the weighted arm coming to rest in the manner of a pendulum. Thus it is apparent 50 that for approximately one-half of a revolution the cutting and shearing rollers are rotated idly and at a slow rate of speed, the gravity controlled arm serving to rapidly rotate said members for the last half revolution whereby the knife will sever the pad 55 and clear the same, causing an intermittent cutting motion that is determined by the diameter of the gears. It is also apparent that I may, if desired, provide a suitable buffer for absorbing the shock incidental to 60 drop of the arm 24 to prevent the same from rocking back and forth, it being observed that the knife, in assuming its normal position of rest, is beyond the path of travel of an uncut pad. 65 Motion is imparted to the lower draw roller 17' through a pinion 28, which pinion is mounted upon a main drive shaft 29 and meshes with a gear-wheel 28', the same being fast upon the shaft of the draw roller 70 17'. Motion is transmitted from the main drive shaft to the counter-shaft 5 through a belt gear connection as shown. 75 It is apparent from the foregoing described apparatus that the three strips of 80 paper A, B and C are all directed to the mouth of the forming tube, at which point they are piled one upon the other and that prior to their assemblage the cushion strip is crimped and the enveloping strip receives 85 longitudinal lines of adhesive material adjacent to the edges of a solid paraffin surface, which surface is so coated for the purpose of preventing adhesion of the completed pad to the highly polished articles to 90 which it is applied. The piled strip members are then passed through the forming sleeve and folded and glued to form a tube which is cut in the desired lengths and when so formed the cushion strip will adhere to the 95 seam side of said tube, while the lower face of said cushion strip is caused to adhere to the reinforcing strip. Thus the corrugations are protected by two thicknesses of 100 paper whereby there is no liability to imprint upon the article packed, which article receives the unbroken paraffin surface of the pad, while the seam side is entirely removed therefrom. 105 I claim: 110

1. A method of forming tubular packing pads, consisting of providing a flat enveloping strip, a flat protecting strip and a flat cushion strip, continually feeding the same at a uniform speed, transversely corrugating the cushion strip, gluing the lower face of the same, gluing the upper face of the enveloping strip adjacent to its edges, thereafter causing the said strips to be piled one upon the other in their travel, folding and lapping the edges of the enveloping strip about the cushion and protecting strip to form a tube, whereby the cushion strip is caused to adhere to the inner surface of the seam side of said enveloping strip and to 115 the adjacent face of the protecting strip, distributing glue between the lapped edges of said enveloping strip to seal the same, and thereafter longitudinally scoring the completed pad to break down the corruga- 120

tions of the cushion strip at intervals, whereby said packing is rendered longitudinally pliable.

2. A method of forming tubular packing pads consisting of providing a flat enveloping strip, a flat protecting strip and a flat cushion strip, continually feeding the same at a uniform speed, transversely corrugating the cushion strip, gluing the lower face of the same, gluing the upper face of the enveloping strip adjacent to its edges, paraffining said enveloping strip between its glued surfaces, thereafter causing the said strips to be piled one upon the other in their travel, folding and lapping the edges of the enveloping strip about the cushion and protecting strip to form a tube, whereby the cushion strip is caused to adhere to the inner surface of the seam side of said enveloping strip and to the adjacent face of the protecting strip, distributing glue between the lapped ends of said enveloping strip to seal the same, and thereafter longitudinally scoring the completed pad to break down the corrugations of the cushion strip thereof at intervals, whereby said packing is rendered longitudinally pliable.

3. A method of forming tubular packing pads consisting of providing a flat enveloping strip, a flat protecting strip and a flat cushion strip, continually feeding the same at a uniform speed, transversely corrugating the cushion strip, gluing the lower face of the same, thereafter causing the said strips to be piled one upon the other in their travel, folding and lapping the edges of the enveloping strip about the cushion and protecting strip to form a tube, and whereby the cushion strip is caused to adhere to the inner surface of the seam side of said enveloping strip and to the adjacent face of the protecting strip, distributing glue between the lapped ends of said enveloping strip to seal the same, and thereafter longitudinally scoring the completed pad to break down the corrugations of the cushion strip thereof at intervals, whereby said packing is rendered longitudinally pliable.

4. In an apparatus for forming tubular packing pads from strips of paper having a tubular forming sleeve, an enveloping strip carrying reel, a protecting strip carrying reel, and a cushion strip carrying reel; the combination of a pair of corrugating rolls interposed between the cushion strip carrying reel and sleeve mouth between which said cushion strip is adapted to travel, a glue distributing means interposed between the corrugating rolls and sleeve mouth over which the said cushion strip is adapted to travel, glue distributing means adapted to engage the under side of the enveloping strip intermediate of its edges, spools arranged to guide the enveloping strip, protector strip and cushion strip in their mentioned order one upon the other to the mouth of the aforesaid forming sleeve, enveloping strip edge gluing means disposed at the discharge end of the tubular forming sleeve, and scoring draw rolls disposed beyond said edge gluing means.

5. In an apparatus for forming tubular packing pads from strips of paper having a tubular forming sleeve, an enveloping strip carrying reel, a protecting strip carrying reel, and a cushion strip carrying reel; the combination of a pair of corrugating rolls interposed between the cushion strip carrying reel and sleeve mouth between which said cushion strip is adapted to travel, a glue - distributing means interposed between the corrugating rolls and sleeve mouth over which the said cushion strip is disposed at the discharge end of the tubular forming sleeve, and scoring draw rolls disposed beyond said edge gluing means.

6. In an apparatus for forming tubular packing pads from strips of paper having a tubular forming sleeve, an enveloping strip carrying reel, a protecting strip carrying reel, and a cushion strip carrying reel; the combination of a pair of corrugating rolls interposed between the cushion strip carrying reel and sleeve mouth between which said cushion strip is adapted to travel, a glue - distributing means interposed between the corrugating rolls and sleeve mouth over which the said cushion strip is adapted to travel, spools arranged to guide the enveloping strip, protector strip and cushion strip in their mentioned order one upon the other to the mouth of the aforesaid forming sleeve, enveloping strip edge gluing means disposed at the discharge end of the tubular forming sleeve, and scoring draw rolls disposed beyond said edge gluing means.

7. A method of forming tubular packing pads consisting of providing a flat enveloping strip and a flat cushion strip, continually feeding the strips at a uniform speed, transversely corrugating the cushion strip and gluing the high points of the lower face of the same during the travel of said strip, thereafter causing the strips to be piled one upon the other in their travel, folding and lapping the enveloping strip about the corrugated cushion strip to form a tubular jacket for the latter whereby said cushion strip is caused to adhere to the enveloping strip, distributing glue between the lapped edges of said enveloping strip to seal the

same, and thereafter longitudinally scoring the completed pad to break down the corrugations of the cushion strip at intervals whereby said packing is rendered longitudinally pliable.

8. A method of forming tubular packing pads consisting of providing a flat enveloping strip and a transversely corrugated cushion strip, continuously feeding the strips at a uniform speed in the same direction, depositing glue upon one of said strips during its travel, thereafter causing the strips to be piled one upon the other in their travel, whereby the same are adhesively secured, folding and lapping the free edges of the enveloping strip about the cushion strip to form a tubu-

lar jacket for the cushion strip, distributing glue between the lapped edges of the aforesaid enveloping strip to seal the same and thereafter longitudinally scoring the completed pad to break down the corrugations of the cushion strip at intervals whereby said packing pad is rendered pliable longitudinally.

In testimony that I claim the foregoing I have hereunto set my hand at Oshkosh in the county of Winnebago and State of Wisconsin in the presence of two witnesses.
